UNITED STATES PATENT OFFICE.

WALTER J. TAYLOR, OF SACO, MONTANA.

CALIPER-REGISTER.

1,163,794.

Specification of Letters Patent. Patented Dec. 14, 1915.

Application filed April 7, 1915. Serial No. 19,682.

To all whom it may concern:

Be it known that I, WALTER J. TAYLOR, a citizen of the United States, residing at Saco, in the county of Valley and State of 5 Montana, have invented certain new and useful Improvements in Caliper-Registers, of which the following is a specification.

The present invention relates to certain new and useful improvements in the construction of calipers, dividers and like instruments, and has for its object to provide a device of this character which includes a novel form of registering device for indicating with accuracy the distance between 15 the points.

Further objects of the invention are to provide a device of this character which is comparatively simple and inexpensive in its construction, which will not interfere in any 20 manner with the use of the calipers or other instrument in the usual manner, which will indicate with accuracy the distance between the points of the instrument and thereby by eliminate the necessity of using a separate 25 scale in connection therewith, and which embodies a mechanical construction not liable to get out of adjustment or repair.

With these and other objects in view, the 30 invention consists in certain novel combinations and arrangements of the parts as will more fully appear as the description proceeds, the novel features thereof being pointed out in the appended claims.

For a full understanding of the invention, 35 reference is to be had to the following description and accompanying drawing, in which:—

Figure 1 is a plan view of calipers constructed in accordance with the invention. 40 Fig. 2 is a similar view with portions broken away and shown in section to illustrate more clearly the details of construction. Fig. 3 is an enlarged transverse section view through the head of the calipers, showing the pivotal 45 connection and gearing between the plates, and Fig. 4 is a detail plan view of the dial plate.

Corresponding and like parts are referred to in the following description and indicated in all the views of the drawing by the 50 same reference characters.

For the purpose of illustration the invention is shown as embodied in calipers, although it will be understood that it can be 55 used with equal advantage in connection with dividers and other similar instruments.

Referring to the drawings, the numerals 1

and 2 designate the opposed legs of the calipers, the free ends of the legs being curved outwardly and then bent inwardly in the 60 usual manner to provide the respective points 1^a and 2^a which are employed in using the instrument. A leaf spring 3 which has one end thereof secured to the leg 1 while the opposite end thereof engages the leg 2 65 normally tends to force the legs apart. A keeper 4 is pivotally connected at 5 to the leg 2 and loosely receives the leg 1 between the arms thereof. An adjusting screw 4^a is threaded in the closed end of the keeper 4 70 and engages the leg 1 so that by manipulating the adjusting screw the legs of the calipers can be accurately set in the required manner.

Rigid with the leg 1 at the pivot end 75 thereof is a dial plate 6, the periphery of the plate being provided with suitable graduations 7, while the central portion of the plate is formed with a large circular depression 6^a, the base of the depression being 80 provided at the center thereof with a short upstanding boss 8 surrounding the pivot opening 9, and at the periphery thereof with an annular rack 10. Fitted within the mouth of the depression 6^a of the dial plate 85 6 is a second and somewhat smaller dial plate 11 which is provided at the periphery thereof with graduations 12 adapted to coöperate with the graduations 7 of the dial plate 6 to indicate with accuracy the exact 90 distance between the points 1^a and 2^a of the legs of the calipers. The inner face of the dial plate 11 is provided at the periphery thereof with an annular rack 13 similar to the rack 10 of the dial plate 6 and having an 95 opposed and spaced relation thereto. The central portion of the dial plate 11 is also provided with a short boss 14 corresponding to the boss 8 of the dial plate 6.

Interposed between the dial plates 6 and 100 11 and arranged within the depression 6^a of the former is a disk 15 to which the leg 2 of the calipers is rigidly connected, the said leg passing loosely through a suitable clearance opening 16 provided in one side of the 105 depression 6^a. A pivot bolt 17 passes centrally through the two dial plates 6 and 11 and the disk 15 so as to hold the members together and at the same time admit of a pivotal movement thereof. The disk 15 is provided at substantially diametrically opposite points with openings within which small gear wheels 18 are mounted, said gear wheels being mounted upon radially dis-

posed pins and projecting laterally from the faces of the disk 15 so as to engage the racks 10 and 13 of the respective dial plates 6 and 11.

5 With this construction, it will be obvious that when the legs of the calipers are moved away from each other the dial plates will have a relative rotary movement which will be magnified or increased by the action of 10 the small gear wheels 18. When the points 1^a and 2^a of the caliper legs are together, the zero points of the two sets of graduations 7 and 12 of the respective dials 6 and 11 will be together. However, when the legs 15 of the calipers are moved apart the dial 11 will be rotated upon the dial 6 so that the two sets of graduations 7 and 12 will assume a relative position depending upon the magnitude of movement of the caliper legs and 20 the distance between the points 1^a and 2^a. One set of the graduations may be arranged to act as a vernier, thereby enabling great accuracy to be obtained in measuring and reading the distance between the points of 25 the calipers.

Having thus described the invention, what I claim as new and desire to secure by Letters Patent, is:—

1. A caliper or like instrument, including 30 a pair of pivotally connected legs, a dial rigid with one of the legs, a concentric dial mounted upon the first mentioned dial, a plate rigid with the other leg, a single pivot member for the two dials and the plate, and 35 an operative connection between the plate and the dials for rotating the dials relative to each other when the legs are swung apart, said dials being provided with coöperating graduations for indicating the distance 40 between the free ends of the legs.

2. A caliper or like instrument, including 45 a pair of legs, a dial rigid with one of the legs, a second dial concentric with the first mentioned dial, said dials being provided upon adjacent faces with corresponding 50 racks, a disk interposed between the dials and rigid with the other leg, a pivot pin connecting the two dials and the disk, and a gear wheel carried by the disk and engaging the corresponding racks of the two dials, so that the dials will be rotated relative to 55 each other when the caliper legs are swung apart, said dials being provided with coöperating graduations for indicating the distance between the free ends of the legs.

3. A caliper or like instrument, including 60 a pair of legs, a dial rigid with one of the legs and formed with a central depression, the base of the depression being provided with an annular rack, a second dial arranged within the mouth of the depression 65 of the first dial and provided upon the inner face thereof with an annular rack having a

spaced and opposed relation to the annular rack of the first mentioned dial, a disk interposed between the two plates and rigidly connected to the opposite leg of the caliper, and a gear wheel journaled upon the disk and meshing with the annular racks of the two dials so that the dials will receive a relative rotation when the caliper legs are swung apart, said dials being provided with coöperating graduations for indicating the distance between the free ends of the caliper legs. 75

4. A caliper or like instrument, including a pair of legs, a dial rigid with one of the legs and provided with a central depression and pivot opening, the base of the depression being provided with a boss surrounding 80 the pivot opening and an annular rack, a second dial fitted within the mouth of the depression of the first dial and having a pivot opening, the inner face of the second dial being provided with a boss surrounding 85 the pivot opening and an annular rack having a spaced and opposed relation to the annular rack of the first dial, a disk interposed between the dials and held in a slightly spaced relation to the two dials by the before mentioned bosses, a pivot pin passing through the pivot openings of the two dials and the disk, said disk being rigid with the other leg of the caliper, and a gear wheel mounted upon the disk so as to project from 90 opposite sides thereof and engage the annular racks of the dials and produce a rotary movement of the dials when the caliper legs are moved apart, the before mentioned dials being provided with coöperating graduations for indicating the distance between the 95 free ends of the caliper legs.

5. A caliper or like instrument, including a pair of pivotally connected legs, a dial rigid with one of the legs, a concentric dial 105 mounted upon the first mentioned dial, a plate rigid with the other leg, a single pivot member for the two dials and the plate, an operative connection between the plate and the dials for rotating the dials relative to 110 each other when the legs are swung apart, the said dials being provided with coöperating graduations for indicating the distance between the free ends of the legs, a spring normally tending to swing the legs apart, 115 a keeper carried by one of the legs, and an adjusting screw threaded within the keeper for engagement with the other leg for accurately setting the calipers in the required manner. 120

In testimony whereof I affix my signature in presence of two witnesses.
